[57] **CLAIM**

The ornamental design for a light switch plate with digital thermometer, as shown and described.

DESCRIPTION

FIG. 1 is a top view of the first embodiment of a light switch

with digital thermometer showing my new design.

FIG. 2 is a perspective view thereof.

FIG. 3 is a right side view thereof.

FIG. 4 is a left side view thereof.

FIG. 5 is a rear view thereof.

FIG. 6 is a front view thereof.

FIG. 7 is a bottom view thereof.

FIG. 8 is a top view of the second embodiment of a light switch plate with digital thermometer showing my new design.

FIG. 9 is a perspective view thereof.

FIG. 10 is a right side view thereof.

FIG. 11 is a left side view thereof.

FIG. 12 is a rear view thereof.

FIG. 13 is a front view thereof.

FIG. 14 is a bottom view thereof.

FIG. 15 is a perspective view of the third embodiment of a light switch plate with digital thermometer showing my new design.

FIG. 16 is a top view thereof.

FIG. 17 is a right side view thereof.

FIG. 18 is a left side view thereof.

FIG. 19 is a rear view thereof.

FIG. 20 is a front view thereof.

FIG. 21 is a bottom view thereof.

FIG. 22 is a perspective view of the fourth embodiment of a light switch plate with digital thermometer showing my new design.

FIG. 23 is a top view thereof.

FIG. 24 is a right side view thereof.

FIG. 25 is a left side view thereof.

FIG. 26 is a rear view thereof.

FIG. 27 is a front view thereof; and,

FIG. 28 is a bottom view thereof.
